Primary Examiner — George D. Kirschbaum*Assistant Examiner* — Maria J Edwards(74) *Attorney, Agent, or Firm* — Ward and Smith, P.A.; Ryan K. Simmons(57) **CLAIM**

The ornamental design for a bridging termination clip, as shown and described.

DESCRIPTION

FIG. 1 is a perspective view of the bridging termination clip showing a new design;

FIG. 2 is a front view thereof;

FIG. 3 is a rear view thereof;

FIG. 4 is a right side view thereof, the left side being a mirror image of the right side;

FIG. 5 is a top plan view thereof;

FIG. 6 is a bottom plan view thereof; and,

FIG. 7 is another perspective view of the bridging termination clip in an installed configuration.

In the drawings the dash-dash broken lines are for the purpose of illustrating environment only and form no part of the claimed design.

1 Claim, 5 Drawing Sheets(56)
